UNITED STATES PATENT OFFICE.

ALFRED F. MORRELL, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

BOX-MOTION CONNECTER.

Application filed November 25, 1924, Serial No. 752,222.

To all whom it may concern:

Be it known that I, ALFRED F. MORRELL, a citizen of the United States, residing at Worcester, in the county of Worcester and 5 State of Massachusetts, have invented a new and useful Box-Motion Connecter, of which the following is a specification.

This invention relates to improvements in box motions and more particularly to motions of this type which are employed on 10 looms having drop boxes on both ends.

It is the principal object of my invention to provide a two part driving connection between the box motion at one end of the 15 loom and the actuating mechanism for the boxes at the opposite end of the loom so constructed that proper adjustment may be made to permit the boxes actuated by the driving connections to be properly aligned 20 with the race of the lay.

It is a further object of my invention to provide a safety device to prevent damage to the boxes for the box motion should a 25 shuttle be improperly boxed when the boxes start to move.

Because of the construction set forth hereinafter I am enabled to construct box motions without knowledge of the width of the looms to which they are to be applied. It 30 has been the practice heretofore in motions of the type shown herein to provide the box motion with a driving shaft formed in one piece, one end of the shaft being connected to the box motion and the other end extending 35 across the loom, and because of this construction it has not been possible to build box motions without knowing the width or length of the looms to which they were to be applied. It is therefore a further object 40 of my invention to provide a box motion acting through a rotary shaft which shall be applicable with equal facility to looms of different widths.

With these and other objects in view 45 which will appear as the description proceeds, my invention resides in the combination and arrangement of parts hereinafter described and set forth in the claims.

In the accompanying drawings wherein 50 I have shown a convenient embodiment of my invention,

Fig. 1 is an end elevation of box motion parts sufficient to show the application of my invention thereto.

Fig. 2 is a front elevation of the construction shown in Fig. 1,

Fig. 3 is an enlarged vertical section taken through coupling on line 3—3 of Fig. 1, and

Fig. 4 is a vertical section on line 4—4 of Fig. 3.

Referring to the drawings it will be seen that I have provided a loom frame 10 to which is secured a frame 11 through which extends driving shaft 12 of the loom. A master gear 13 on said shaft is provided with sections of teeth indicated at 14 which cooperate at proper times with the actuating pinions for the box motion, two of said pinions being shown herein as at 15 and 16, respectively. The upper pinion 15 is operative through connections not shown to actuate the boxes on that end of the loom adjacent to the gear 13 and the lower gear 16 is operative through mechanism to be described to actuate the boxes on the remote 75 end of the loom.

Associated with the gear 16 is a sliding tooth 17 which is movable under control of the angle lever 18 toward and from the master gear, said tooth when in alignment with the master gear initiating the rotation of gear 16 by one of the segments 14 and when out of alignment with the master gear permitting said segments to pass the gear 16 without actuating the same. The position 80 of the tooth 17 is controlled by means of link 19 which may be actuated by any approved pattern mechanism. The matter thus far described is very well known in the art and forms no part of my present invention.

The gear 16 is fastened to the outer end of a shaft section 30, causing the latter to undergo a half revolution each time said pinion 16 is actuated by the master gear. The inner end of said section 30 may be reduced as at 31 and has secured thereto a coupling member 32 by means of a shear pin 33. Said coupling 32 is further provided with a flange 34 in which are formed arcuate slots 35 through which extend a plurality of bolts 36. Said bolts 36 extend through a flange 37 formed on a second coupling member 38 which is keyed or otherwise secured to the reduced end 39 of a shaft section 40. The flanges may be of substantially the same proportions and are fastened together tightly by means of the bolts 36, thus requiring the sections 30 and 100 105

40 to move in unison so long as the shear pin 35 is not disrupted. In order that the flanges may be properly related to each other the reduced end 31 extends into the 5 bore 41 of coupling portion 38, thus centering the coupling portions. The section 30 is supported by bearing 49 carried by the frame 11.

As indicated in Fig. 2 the farther end of 10 said shaft 40 extends through a bearing 42 and has secured thereto a crank arm 43 from which extends a stud or driving pin 44. Pivoted to the loom frame as at 45 is a lever 46 one end of which is slotted as at 15 47 to receive the driving pin 44 and the other end of which is connected as by link 48 to the box lifter rod (not shown) for the adjacent boxes.

In operation the half rotation of the shaft 20 sections 30 and 40 cause the crank 43 to move through 180° to move the lever 46 from the full line position shown in Fig. 1 to the dotted line position. Should the shuttle become caught between the lay and the boxes 25 as the latter move the pin 33 will be sheared off and thus protect the shuttle and the shuttle box. I have shown my invention applied to a loom having two shifting shuttle boxes on each end thereof but the invention is 30 not limited to such a type of loom. When it is desired to effect angular adjustment of the shaft sections 30 and 40, the bolts 36 are loosened and the coupling members adjusted with respect to each other, the end 35 of the section 30 which projects into the bore 41 serving to align the coupling members when the bolts are loose.

From the foregoing it will be seen that I 40 have provided a box motion wherein the connection between the box motion and the remote boxes can be disrupted when occasion requires. Also, adjustment between the shaft section may be obtained conveniently and the parts held in alignment while the 45 adjustment is being made. Furthermore, the shorter section 30 makes it possible to build the box motion complete with the pinion 16 in place independently of the length of the loom to which the motion is to be 50 applied, the section 40 varying with the particular loom to which the motion is attached.

Having thus described my invention it will be apparent that changes and modifications may be made therein by those skilled 55 in the art and I do not wish to be limited to the details herein disclosed, but what I claim is:

1. In a box motion applicable to looms of varying widths, box lifting mechanism, means to actuate said mechanism, and connection between said means and mechanism, said means comprising a portion of fixed and invariable length associated permanently with the means to actuate the lifting mechanism, and said connections comprising 60 also a second member having driving connections with the first member and being of variable length depending upon the length of the loom to which said box motion is to be applied.

2. In a box motion for looms, box lifting mechanism, means to actuate said mechanism, and a driving connection between said means and mechanism, said means including a shaft formed in two parts, a coupling 75 formed in two parts, one part of the coupling being connected to one part of the shaft and the other coupling being connected to the other shaft, and means to adjust the angular position of said coupling members 80 with respect to each other.

3. In a box motion for looms, mechanism to lift the boxes, means to actuate said mechanism, and connections between said means and mechanism including aligned shaft sections, a coupling member secured to the adjacent ends of each of said shaft sections, one of said shaft sections extending through the member secured thereto and into the other member, and means to adjust the angular position of the flanges with respect to each other.

4. In a box motion for looms, box lifting mechanism, a box motion to actuate the same, and driving connections between the 95 box lifting mechanism and the driving mechanism, said connections including a two part shaft, a coupling to connect said shaft parts together, and a shear pin connecting said coupling to one of the shaft parts to be 100 disrupted when free motion of the shafts is resisted.

5. In a box motion for looms, a box lifting mechanism, a regularly rotating master gear, a pinion to be actuated by the gear, 105 a shaft section on which said pinion is mounted, a second shaft section operatively connected to said box lifting mechanism, and means common to said shaft sections to connect the same together and cause them to 110 rotate in unison.

In testimony whereof I have hereunto affixed my signature.

ALFRED F. MORRELL.
